(57) **CLAIM**

The ornamental design for a diffuser device for deodorants, as shown and described.

DESCRIPTION

FIG. 1 is a first perspective view of a diffuser device for deodorants showing my new design;

FIG. 2 is a second perspective view thereof;

FIG. 3 is a third perspective view thereof;

FIG. 4 is a fourth perspective view thereof;

FIG. 5 is a fifth perspective view thereof;

FIG. 6 is a bottom plan view thereof;

FIG. 7 is a right side elevational view thereof;

FIG. 8 is a rear elevational view thereof;

FIG. 9 is a left side elevational view thereof;

FIG. 10 is a top plan view thereof; and,

FIG. 11 is a front elevational view thereof.

The broken line showing of the plugs and the top portion of the diffuser device is for illustrative purposes only and forms no part of the claimed design.
